UNITED STATES PATENT OFFICE.

BENJAMIN G. GILBOUGH, OF SAN GABRIEL, CALIFORNIA.

COVER FOR LEAF SPRINGS AND METHOD FOR MAKING.

Application filed August 3, 1925. Serial No. 47,790.

This invention relates to means for substantially enclosing laminated vehicle springs. More particularly the present invention relates to a cover and method of making and applying the same for leaf or laminated springs of vehicles.

It is an object of the invention to provide a sectional rebound cover structure, for laminated springs, of a form that may be easily fitted and secured and in which the sections are each substantially independent of the other and which envelop a porous medium laid upon and around the spring body to be enclosed.

15 An object is to provide a sectional spring cover consisting of a number of independent clips having a minimum degree of relative movement and at the same time each being substantially free from any flexure or bending action and therefore preventing crystallization of the clip members as results in spring covers including parts which must constantly flex, bend or weave in conformity with the bending of the spring structure.

25 An object is to provide a means and method whereby a spring cover can be readily selected according to size of the spring to be covered and readily applied, all with the object of requiring but a small investment in parts 30 to be carried in stock and yet enable the assembly and application of parts readily and quickly according to various sizes of springs. In this connection, it is an object to provide a spring cover having sections of extremely 35 simple form and which can be carried in stock in blank or flat form to conserve space, and which can be readily bent to the desired spring-fitting outline when they are to be, and as, applied. It also is an object to provide a sectional spring covering or element 40 which may be readily removed and therefore enable the renewal of parts without the removal of the entire device from its spring.

Another object is to provide a shoe having 45 sections constructed and arranged to prevent undue wear as upon the parts of the device. Another object is to provide for the introduction of a lubricant at any point along the spring cover and eliminate the requirement 50 of fittings and appliances and eliminating the use of ordinary type of grease or oil cups and the like.

An object is to provide a covering which is 55 formed of independently moving clips covering the entire working portion of the spring

and which, while preventing excessive separation of the leaves under rebound, at the same time will not produce an undesired degree of resistance to the action of the leaves of the spring.

60 An important object is to provide a spring cover devoid of parts which must, within themselves, have a flexible action, and therefore an object is to provide a structure which will be free from crystallization due to flexure 65 of the spring and at the same time an object is to provide a cover which is practically form-fitting and will be sufficiently tight to retain the lubricating medium and enable the same to flow rapidly into the interstices between 70 the leaves of the spring and which also will allow ready atmospheric action for the forcing of the lubricant into the interstices during spring action. In this connection, an object is to provide a covering which will operate to maintain such a head of oil as to cause 75 it to flow by gravity to and between the leaves of the spring which is enclosed.

Other objects and advantages will be made manifest in the following specification of embodiments of the invention illustrated in the accompanying drawings, wherein:

Figure 1 is a plan, partly broken away, showing the device as applied to one end of a laminated spring.

Figure 2 is a longitudinal section of the device as applied.

Figure 3 is a side elevation of the device.

Figure 4 is a cross section on line 4-4 of Fig. 2.

90 Figure 5 is a sectional view of a modified form of the device.

Figure 6 is a perspective of one of the inverted clips and its shoe forming a cover unit.

Figure 7 is an elevational and sectional 95 view showing a modified form of the clip-cover.

Figure 8 is a cross section on line 8-8 of Fig. 7.

Figure 9 is a perspective of an inverted clip 100 of the type shown in Fig. 7.

Figure 10 is a perspective of an inverted clip top.

Figure 11 is a perspective of an inverted clip shoe.

105 Figure 12 shows a system of various sizes of clip tops.

In Figures 1 to 6, inclusive, and in Fig. 12, one embodiment of the improved cover is shown as consisting of a number of clip units. 110

Each unit consists of a substantially U-shaped top member 2, the side walls 2^a of which are perforated to receive any suitable fastening means as rivets 4. These rivets pass through flanges 5^a of a longitudinally extending shoe 5 which includes a forwardly extending tongue 5^b and a rearwardly extending short tongue 5^c. The width of the top 2 is such that it is adapted to straddle down over and encompass a porous jacket 6, of any suitable material, such for instance as felt, laid around and substantially encompassing a laminated spring structure S. The porous jacket 6 preferably extends continuously across the bottom and up the sides of the spring and the marginal, overlapping portions of the jacket lie along the top of the spring and form a channel or canal 7 along the top leaf for the ready flow of a suitable lubricant, such as oil, down along the leaf and laterally to the sides of the spring. Thus the lubricant from the channel 7 flows into the side wall portion of the jacket 6 and from these may flow or be forced inwardly by atmospheric pressure into the interstices between the spring leaves.

A complete unit or clip structure is illustrated in Figure 6 in the inverted position. A number of these units are adapted to be aligned along the bending portion of the spring S, as in Figures 1 and 2, with the longer tongue 5^b of one unit projecting well up over and bearing upon the body portion 5 of the next shoe while the shorter, end tongues 5^c projects somewhat from the opposite end of the shoe.

When a series of units is assembled, the flanges 5^a lie substantially in parallelism and are overlapped at their ends by the corners 2^b of the top walls 2^a, which therefore serve to prevent the corners of the flanges 5^b from overlapping each other and at the same time allows the units to weave or shift independently of each other and without any flexure inherently when and as the spring S bends.

The extension of the corners 2^b beyond the contiguous ends of the flanges 5^a permits of the projection of one end of each top element in under and telescopically into the contiguous and outer end of the next section; the top members being shown as converging slightly in Figure 1 to permit of this telescopic action of one unit in the other.

From this it will be seen that when a series of the units have been assembled, they are not directly connected but are free from each other and form a substantial enclosure or cover for the entire working portion of a spring. The provision of the longitudinally extending lubricant channel 7 under the tops 2 between the longitudinal edges of the jacket 6 enables the ready introduction of a lubricant as by the insertion of a tool T beneath an edge of the top of a unit, as in Figure 2, when the top is bent upwardly as shown. By

the use of a tool as shown the lubricant can be injected at any point along the top or along the sides of the spring by merely inserting the tool beneath an edge of a unit.

In Figure 5 the side flanges or walls 2^a of a unit may be of sufficient length as at 2^c to be turned up and around as shown in Figure 5 beneath the flanges 5^a of the shoes 5.

In Figures 7 to 11 inclusive a form of the cover consists of a top section 20 having side walls 20^a and these are inwardly bent or hooked as at 20^c. The shoes of this of this form include plates 25 having upturned flanges 25^a which extend slightly beyond the longitudinal edges of the shoe 25 so as to form shoulders 26, Figure 11. Each shoe has at one end an extending tongue 25^b and at the opposite end a shorter extending tongue 25^c which has an upturned lip 27.

When a series of tops and shoes 20-25 are assembled, as in Figure 9, the hook portions 20^c at the narrower end of each clip extend telescopically into the contiguous wider end of the next clip; this being permitted by the cutaway corners of the end portions 25^c.

Undue longitudinal shifting of the units as to the spring S is prevented by the engagement of the upturned lip 27 of one shoe against the contiguous, inturned hook or flange portions 20^c of a side wall 20^a. The flanges 25^a of each shoe are interhooked beneath the hook portions 20^c and therefore, while permitted to have desirable play, at the same time are sustained and held in assembled position without requirement of extraneous fastening means, such for instance as rivets 4 shown in Figure 6.

One of the important objects of my invention is to provide a system and method enabling a garage or other service establishment to carry in stock, in knocked-down condition for economical storage purposes, a minimum number of parts so that, presented with a given size spring, there may be readily constructed and applied a complete cover consisting of the necessary number and proper size of cover or clip units. In carrying out this feature of the invention, as is illustrated in Figure 12, I provide a suitable series of graduated and properly indexed blanks 2^x representing unbent, top-forming plates which vary only in respect to their lengths 1. Thus, by carrying a suitable number of each of the different lengths of blank plates 2^x, a garage or service establishment may select a suitable number of each type when called upon to fit and cover a spring.

The blanks 2^x of a selected set of duplicates are adapted to be quickly and readily folded to the desired U-shaped form, Figures 6 and 10, and straddled upon the spring to be fitted, and the desired width of shoe 5 or 25 is attached to the applied clip as in Figures 1 or 7, until the entire bending end of the spring

is enclosed; it being understood that the porous jacket 6 is applied to the spring before the metallic clips are attached.

It will be seen, therefore, that the spring cover of the present invention consists essentially of clip units each including practically only two major parts, and these are adapted to be manufactured, distributed and stored in substantially flat form for economy in transportation and storage space and charges.

It will further be seen that the complete cover is adapted to be built up as required on demand of the service establishment, although it is to be understood that if desired the units may be manufactured in substantially complete form in readiness to be assembled upon a spring in series by the mere application of the rivets 4, when such are employed, or by the final bending of the hook portions 20°, as shown in Figure 9, when the device is of this type.

Further embodiments, modifications and variations may be resorted to within the principle of the invention.

What is claimed is:

1. A laminated spring cover consisting of a series of relatively movable units having top and bottom plates each with side flanges which are interconnected beyond the bottom of the spring.

2. A laminated spring cover consisting of a series of relatively movable units arranged in a series along a spring and having contiguous ends telescoping in each other and each unit having a tongue extending into the next to bridgeleaf shoulders of the spring, the units each comprising top and bottom elements with overlapping side flanges; said tongue extending beyond the ends of the side flanges of its unit element.

3. A laminated spring cover consisting of a plurality of units arranged in a series along a spring and having contiguous ends telescoping in each other whereby the cover as a whole is adapted to bend without the flexing of any one of the units inherently, each unit including a box section having side flanges projecting beyond the spring, and a plate having side flanges overlapped by the projecting portions of the flanges and connected therewith.

4. A laminated spring cover comprising a

series of relatively movable units, each unit consisting of a top element having side flanges to lie against and project from the spring, a bottom element having downturned side flanges overlapped by the side flanges which project, and means for attaching the top element and the bottom element together to complete a unit.

5. A laminated spring cover consisting of a plurality of independent units, each unit comprising a top element having side flanges, a bottom element having side flanges, and means for attaching the top element and the bottom element together to complete a unit; the bottom element having a tongue at one end extended beyond the flanges to lap within and rest upon the bottom of the next contiguous unit.

6. A laminated spring cover consisting of a series of relatively independent units, each unit consisting of a top element having side flanges to lie against the side of the spring, a bottom element having downturned side flanges extending away from the spring, and means for attaching the top element and the bottom element together to complete a unit, said means including rivets passing through the overlapping side flanges of the unit below the leaves of the spring.

7. A laminated spring cover consisting of a series of relatively independent units, each unit consisting of a top element having side flanges, a bottom element having side flanges, and means for attaching the top element and the bottom element together to complete a unit, said means including inwardly turned, hook-like flange portions provided along the side flanges of the top element, and which overlap the flanges of the bottom element.

8. A laminated spring cover consisting of a series of independent units each including a top element having outer side flanges and a bottom element having inner side flanges bearing on respective sides of the outer flanges; the inner flanges of the series being substantially in alignment along the sides of the units, whereby their contiguous ends will abut to limit longitudinal shifting of the units, the units having limited free relative longitudinal movement.

BENJAMIN G. GILBOUGH.
